UNITED STATES PATENT OFFICE.

GEORGE W. CARTER AND R B HAYDEN, OF SAN ANGELO, TEXAS.

CASING-PULLING DEVICE.

1,418,533.

Specification of Letters Patent. Patented June 6, 1922.

Application filed September 24, 1920. Serial No. 412,477.

To all whom it may concern:

Be it known that we, GEORGE W. CARTER and R B HAYDEN, both citizens of the United States, residing at San Angelo in the county of Tom Green and State of Texas, have invented a certain new and useful Improvement in Casing-Pulling Devices, of which the following is a full, clear, and exact description.

10 In removing the casings from wells, particularly oil-wells, considerable difficulty is encountered, due in part to the tenacity with which the casing adheres to the earth surrounding it and the concrete used in joining the sections of casing of different diameters, and in part to sections of the casing becoming out of line; and the need of a practical device for pulling such casings has long been felt.

20 Due to the great depth of wells, and the restricted space in which operations must be carried on, and the impossibility of observing such operations at appreciable depths, a casing pulling device, to be practical, must be of the simplest possible construction; of few parts, compact, strong and durable; and, moreover, it must be provided with means, which, should it be incapable of raising the casing once the device is in 30 operative position, will effect its disengagement from the casing and permit of its being raised to the surface.

One object of this invention is, therefore, to provide a casing pulling device of simple, 35 compact and durable construction, of such conformation as will permit of its being lowered into a well casing without being obstructed in its descent by irregularities or bends in the casing, and which will, when 40 in operative position, engage the casing with such tenacity as to insure its proper operation.

Another object is to provide the device with mechanism operable through devices 45 controlled from the surface, whereby the device may be rendered inoperative and its recovery made possible.

With these and other objects in view, the invention consists in a casing pulling device 50 comprising a housing provided with a projecting lip, and a pivoted dog carried by the housing and adapted when in operative position to force said lip into intimate operative engagement with the interior wall of 55 the casing, this dog adapted to be operated by a trip mechanism to move it into inop-

erative position wholly within the housing and maintain it in such position, means being provided for manipulating the trip mechanism by an operator stationed at the 60 surface, all as will be hereinafter explained and finally claimed.

In the accompanying drawings illustrating the invention, in the several figures of which like parts are similarly designated, 65 Figure 1 is an elevation of the device looking at the side carrying the trip mechanism. Fig. 2 is a partial longitudinal vertical section, taken in a plane at right angles to Fig. 1, showing the parts in inoperative position. Fig. 3 is a view similar to Fig. 2 but showing the parts in operative position. Fig. 4 is a top view of the device. Figs. 5, 6 and 7 are views showing various steps in the operation of the device within a well 75 casing. Fig. 8 illustrates a preferred form of messenger for actuating the trip mechanism.

The device comprises essentially a housing 1 made preferably of some tough, heavy 80 metal, preferably cylindrical in form and having its lower or leading end tapered to a conical point 2, its opposite end being shouldered as at 3, for a purpose later appearing, and preferably terminating in a 85 frusto-conical extension 4 carrying an eye 5 or other means by which it may be suspended from a suitable cable. It will be seen that by making the device in this form, all projections which might impede it when 90 being lowered into a well casing, are removed and a smooth surface is presented.

Adjacent the lower end of the housing 1 is mounted a lip 6, made preferably of hardened tool steel, its attaching portion 7 95 being here shown as of dovetail formation and seated in a complementary recess in the housing with a tight press fit to prevent its unwarranted detachment therefrom.

The housing is formed with a diametrically arranged slot 8 extending through it from face to face, and in this slot is pivotally mounted on a bearing-screw 9 a dog 10 provided with a plurality of teeth 11, more particularly described hereinafter. It 100 will be observed, by reference particularly to Fig. 2 that the pivot 9 of the dog 10 is so arranged that the dog has, at all times, a tendency to drop to the position shown in Fig. 3, and also that the base 12 of the slot 110 8 is of such shape that, when the dog is in inoperative position, any foreign matter will

tend to pass out of the slot and prevent fouling thereof and of the dog.

Mounted in suitable guides 13, here shown as tongue and groove guides, is a latch plate 14 provided with a slot 15 the ends of which cooperate with a stud 16 to limit the vertical movement of the plate, and this stud is surrounded by a helical spring 17 mounted in a recess 18 in the housing 1, one of its ends bearing against the base of this recess and the other against the inner face of the latch plate adjacent the slot 15 to offer frictional resistance to the movement of the plate so that it will remain in adjusted position and will not drop of its own weight. The plate 14 is set in from the periphery of the housing, as shown, so that it will not contact with the casing wall and be injured or impeded in its operation thereby.

As shown in Fig. 3, when the dog is in operative position, the plate 14 is raised, and its lower end just clears a lug 19 on the dog 10, and the thrust of the dog is taken by the bottom wall of the slot 8 and when pressure is applied to the upper end of the latch plate, as will be later described, this pressure will be communicated to the lug 19 through the lower end of the plate 14 and will move the dog to the position shown in Fig. 2 and hold it in such position, as will be obvious. This latch plate and lug will be hereinafter referred to as the trip mechanism.

It will be noted that the slot 8 is considerably longer than required for the dog shown. This additional length of slot is provided so that dogs of greater length than that shown may be used, as may also dogs of less length, so that by replacing dogs the device may be adapted to casings of all customary diameters.

As shown, the lip 6 is provided with a concave face and has its casing engaging edge inclined upwardly. By so forming it insertion of the lip in the side of the casing is assured, and a sharp cutting edge is obtained.

Referring now particularly to Figs. 5, 6 and 7 wherein various positions of the device relative to the casing are illustrated, the operation of the device is as follows:—In ordinary oil drilling operations, two cables are used, the drilling cable and the slush-bucket cable, and in operating our device we make use of both cables.

When it is desired to raise the well casing herein indicated at 20, we attach the pulling device to the drilling cable 21 by means of the eye 5 in any suitable way. Then the latch plate 14 is set in the position illustrated in Fig. 3 which position permits of free pivotal action of the dog 10. The device is then lowered in the casing, the dog being free to slide along the wall thereof as indicated in Fig. 5, no matter how close to

or how far from the wall of the casing the device may swing. When such a depth in the well is reached, as may be ascertained by reference to the log of the well, that the device will be in that part of the casing which it is desired to pull, the cable 21 is hoisted. This hoisting of the cable pulls upward upon the device and causes the teeth of the device diametrically across the casing and causes the lip 6 to dig into the wall of the casing, as illustrated in Fig. 6. It will be obvious that further hoisting of the cable 21 will carry with it that section of the casing engaged by the device.

If it should become apparent that the casing cannot be pulled, but that more likely, the cable 21 will part under the strain, it then becomes necessary to release the device from the casing. For this purpose we provide a messenger 22, shown in detail in Fig. 8. This messenger comprises a tube 23 provided with a serpentine slot 24 which permits of the messenger being threaded onto the cable 21 so as to have a loose sliding engagement therewith, and it is also provided with means, such as a hole 25, by which it may be attached to the slush-bucket cable 26.

The depth at which the device is located in the casing being known, the messenger 22 is lowered along the cable 21 by means of the slush-bucket cable 26 until it reaches a point slightly above that at which the device is located (as shown in dotted lines in Fig. 7), then it is allowed to drop quickly. This dropping of the messenger will cause it to slide over the portion 4 of the device and strike upon the upwardly projecting end of the latch-plate 14 with sufficient force to move it downward as far as the shoulder 3, hereinabove referred to and also cause the lip 6 to become disengaged from the side of the casing and thus allow the device to drop free of the casing, sufficient slack being allowed in the cable 20 for this purpose, and at the same time raise the dog out of engagement with the wall of the casing and into housed position in the housing 1, and lock it in such position (as shown in full lines, Fig. 7). The messenger 22 is then raised to the surface and detached from the cable and the pulling device is then also raised.

It will be apparent from this description that at no time in the operation of our device is there more than one moving cable in the wall casing at a time. This is of decided advantage due to the fact that as experience teaches, it is practically impossible to raise or lower two cables in a well casing at the same time without having at least one of them become fouled, and where wire cables are used, and such use is almost universal, fouling of such a cable causes it to kink in such a manner as to be thereafter practically

useless, and hence a considerable financial loss.

By reference particularly to Figs. 2 and 3, it will be seen that the teeth 11 of the dog 5 are blunt, with the exception of that one which first comes in contact with the well casing, and that tooth is relatively sharp, so that proper movement of the dog when the device is raised to operative position will 10 be insured. It is to be understood that the dog is in no wise depended upon for a lifting action, but is merely for the purpose of causing the lip 6 to dig into the side of the casing. The teeth of the dog being blunt, 15 the operation of the trip mechanism, composed of the latch-plate 14 and lug 19 of the dog, is facilitated when the messenger 22 strikes against the projecting end of the latch-plate.

20 Although we have herein shown and described a particular embodiment of our invention, it is to be understood that we do not consider it as limited thereto, as various changes may be made in the details of construction and arrangement of parts without departing from the spirit of the invention or the scope of the following claims.

What we claim is:—

1. In a casing pulling device, a housing, 30 a lip carried thereby, a dog pivotally mounted in said housing, and a trip mechanism operated by impact to move said dog to and thereafter maintain it in inoperative position.

35 2. In a casing pulling device, a housing, a stationary lip carried thereby, a dog pivotally mounted in said housing and adapted when in operative position to force said lip into engagement with the casing, and a trip mechanism adapted to move said dog into inoperative position and maintain it therein.

40 3. In a casing pulling device, a housing, means for attaching said housing to a cable by which it may be raised and lowered in a 45 casing, a lip carried by said housing and adapted to engage the casing, a dog pivotally mounted in said housing and adapted when in operative position to force said lip into the wall of said casing, a trip mecha-

nism for moving said dog into inoperative 50 position, and means independent of said device for operating said trip mechanism.

4. In a casing pulling device, a housing, means on said housing whereby it may be suspended from a cable, a single cable attached to said suspending means, a lip carried by said housing and adapted to operatively engage a casing, a dog carried by said housing and adapted when in operative position to force said lip into the wall of said 55 casing, a trip mechanism comprising a latch-plate carried by said housing and a lug carried by said dog, and means independent of said device and adapted to slide on said cable for operating said trip mechanism to 60 cause said dog to move into and be locked in inoperative position and permit of the device being raised from said casing.

5. In a casing pulling device, a housing provided with a slot, a dog pivotally mounted 70 in said slot and adapted when in inoperative position to be completely housed therein, a trip mechanism comprising a latch-plate having a limited sliding movement in said slot, and a lug carried by said dog and 75 cooperating with said plate whereby when said plate is in its elevated position said dog is in operative position and when said plate is lowered it will move said dog into inoperative position and maintain it therein. 80

6. In a casing pulling device, a housing, a casing engaging lip carried thereby, a dog pivotally mounted in said housing and adapted normally to project beyond the same, a latch-plate slidably mounted in said 85 housing and cooperating with said dog to move same into inoperative position, and a messenger adapted to strike upon said plate to move said dog to inoperative position.

In testimony whereof we have hereunto 90 set our hands this 23d day of September A. D. 1920.

GEORGE W. CARTER.
R B HAYDEN.
